UNITED STATES PATENT OFFICE.

RICHARD LABORDA, OF SAN FRANCISCO, CALIFORNIA.

FOOT-OPERATED ELEVATOR.

1,104,199.

Specification of Letters Patent.

Patented July 21, 1914.

Application filed July 11, 1913. Serial No. 779,635.

To all whom it may concern:

Be it known that I, RICHARD LABORDA, a subject of the King of Spain, and a resident of the city and county of San Francisco and the State of California, have invented certain new and useful Improvements in Improved Foot-Operated Elevators, of which the following is a specification.

10 My invention relates to foot operated elevators wherein the car is provided with a spring actuated drum that is adapted to elevate the said car by means of a stationary suspended cable wound thereon, the upper 15 end of the said cable being rigidly secured to the top of the frame work which serves as a guide for the car, and wherein stirrups slidably mounted within the car, are adapted to control the operation of the spring 20 actuated drum and the object of my invention is, to provide improved means for elevating an elevator car.

For a clear comprehension of the device reference should be had to the drawings 25 forming a part of the present specifications wherein like numerals of reference designate similar parts throughout the said specifications and drawings and in which—

Figure 1 is a front broken elevation of the 30 device, disclosing the spring actuated drum, the controlling sprockets and the idler sheave rotatably mounted on the car, and the foot pedals slidably mounted on the said car, the manner in which the cables are secured to the stirrups and sprockets, and the manner in which the lifting cable is secured to the spring actuated drum and the idler sheave. Fig. 2 is a vertical sectional view taken on line X—X of Fig. 1 looking in the 35 direction indicated by the arrow. Fig. 3 is an enlarged side elevation of the sprockets and the idler sheave disclosing the manner in which the said sprockets automatically engage the said sheave and the means for releasing both sprockets from the said sheave for the purpose of lowering the car. Fig. 4 is a vertical sectional view of the 40 spring actuated drum and the governor secured thereto for the purpose of controlling the descent of the car. Fig. 5 is a sectional view of the spring actuated drum disclosing the coiled spring secured thereto and the shaft upon which the said drum is mounted. Fig. 6 is a side elevation of the governor 45 and Fig. 7 is a plan view in section of a

portion of the car disclosing the manner in which the stirrups are mounted therein.

A vertical frame 1, which for convenience in drawing I have illustrated in a vertical position, is adapted to be leaned against the 60 wall of the shelf and has a car 2 slidably mounted therein. Stirrups 3 and 4 are slidably mounted within the car.

At the top of the car 2 are horizontal bars 5 between which is rotatably secured a shaft 6. Rotatably mounted upon the said shaft 6 are the sprockets 7 and 8 which are provided with the clutches 9 and 10, respectively, said clutches 9 and 10 being adapted to engage similar clutches 11 and 12 which 70 are integral with the idler sheave 14. Coiled springs 15 and 16 are coiled about the shaft 6 and are interposed between the sprockets 7 and 8 and the outer bearings of the said shaft. Pivotal secured to the bars 5 are 75 levers 17 and 18 which are adapted to engage the hubs of the sprockets 7 and 8, respectively, for the purpose of disengaging the said sprockets from the idler sheave 14 and moving the same against the tension of 80 the springs 15 and 16, the purpose of which will hereinafter be more fully described. Cords 19 and 20 connect the lower ends of the levers 17 and 18, respectively, and are in turn connected to a central cord 21 so that 85 when the said cord 21 is pulled downward the ends of the said levers 17 and 18 will be moved toward each other and release the sprockets 7 and 8 from the sheave 14.

A stationary suspended cable 22 is secured to the upper portion of the frame 1 and after passing over a guide pulley 23, rotatably mounted within the standards 24 of the car 2, and making a double turn around the sheave 14 is wound around a spring actuated drum 27 which is rotatably mounted upon a fixed shaft 29 secured to suitable supports 28 on the car 2. A coiled spring 26 has one end secured to the fixed shaft 29 the other end thereof being secured to the 90 internal surface of the drum 27. Pins 30 are rigidly secured to one side of the drum. On the outer ends of the pins 30 are pivotally secured the band brakes 32 which are adapted to be engaged by the weighted levers 33 which are also pivotally secured to the pins 30 and adapted to engage the brake bands 32 and press the same against the 95 brake drum 31 rigidly secured to the fixed shaft 29 for the purpose of controlling the 100 descent of the car. Fig. 5 is a plan view in section of a

speed of the drum 27. A suitable housing 34 is provided for the governing mechanism and rotates therewith.

5 A cable 35 is secured to the bottom of the pedals 3 and 4 and passes over a pulley 36 rotatably secured to the bottom of the car 2.

10 A continuous connection 37, having chain portions 37' which are adapted to engage the sprockets 7 and 8, has one end secured to the top of the stirrup 3 and, after passing over the sprocket 7, idler pulley 38 and the sprocket 8, has the other end thereof secured to the top of the stirrup 4.

15 An idler 39 is secured to the top of the car 2 and directly over stirrup 3 and engages the connection 37 so that the connection 37 between the said idler 39 and the stirrup 3 will always be vertical while the said stirrup 3 is moving up or down. A 20 suitable bolt 40 is slidably mounted in the car 2 and is adapted to engage apertures, not shown, in the vertical portion of the frame 1 for the purpose of retaining the car 2 in several positions.

25 The operation of the car is as follows: The tension of the spring S within the drum 27 is sufficient to raise the car 2 and the stirrups 3 and 4 therein when no weight is on the said stirrups or car. The tension of 30 the spring S rotates the drum 27 and winds up the cable 22 thereby elevating the said car 2 to which the said drum 27 is rotatably secured. As the car 2 ascends the stationary cable 22 rotates the drum 14 around which 35 the said cable 22 makes a double turn. When the feet of the operator are placed in the stirrups 3 and 4 his weight is supported by the idler 38 and the connection 37 which engages the said idler 38 and supports the 40 stirrups 3 and 4 to which the said connection is secured. When the weight of the operator is removed from the stirrup 3 and placed on the stirrup 4 the following operation takes place. The tension of the 45 spring S secured to the drum 27 will rotate the said drum and wind up the cable 22 which will elevate the car 2 and cause the sheave 14, secured to the top thereof, to be rotated by means of that portion of 50 the stationary cable 22 which engages it. The weight of the operator or the stirrup 4 will be supported by the chain portion 37' of the connection 37, which engages the sprocket 8, in the following manner: The 55 tension of the spring 16 coiled about the shaft 6 will cause the clutch 10 of the sprocket 8 to engage the clutch 12 of the sheave 14. As the sheave 14 rotates during the upward movement of the car 2 the 60 sprocket 8, to which the said clutch 12 of the sheave 14 is connected, rotates therewith and such rotation is assisted by the weight of the operator on the stirrup 4. From this it is apparent that the weight of 65 the operator on the stirrup 4 will assist

the elevation of the car 2 and the stirrup 3 from which the weight of the operator has been removed. As the car moves upward the stirrup 4 will remain stationary relatively to the frame 1 and the stirrup 3 70 will be elevated by that end of the connection 37 to which it is secured inasmuch as that end must move upward when the end to which the stirrup 4 is secured is stationary and the car is moving upward. 75 When the bottom of the car 2 reaches the stirrup 4 the weight of the operator is transferred to the stirrup 3 which causes the chain portion 37' of the connection 37 to move the sprocket 7 in a direction that will 80 permit the spring 15 to force the clutch 9 of the sprocket 7 into engagement with the clutch 11 of the sheave 14. The tension of the spring S of the drum 27, assisted by the weight of the operator or the stirrup 85 3, will again elevate the car 2 and the stirrup 4, by rotating the sheave 14 and causing the same to ascend the stationary cable 22. Simultaneously, the stirrup 4 will be elevated by the connection 37. 90

When the car 2 has attained the desired elevation it may be retained in that position by maintaining the weight of the operator on either stirrup until the car 2 reaches the bottom of the lowermost stirrup which 95 will prevent the further elevation of the said car inasmuch as the tension of the spring S is not sufficient to raise the weight of the operator.

When it is desired to cause the car to descend the same is accomplished by pulling downward on the cord 21 which will cause the levers 17 and 18 to release both sprockets 7 and 8 from the sheave 14. The governor hereinbefore described will control the descent of the car. 100

It is obvious from the foregoing that I have provided improved means for elevating the car. 105

Having thus described my invention what 110 I claim as new and desire to secure by Letters Patent is—

1. A foot operated elevator comprising a suitable car; a stationary suspension cable; a suitable sheave rotatably mounted on the 115 top of the car and adapted to engage the stationary cable; a spring actuated drum rotatably mounted on the car and adapted to elevate the said car by winding the lower end of the stationary cable thereon; stirrups 120 slidably mounted within the car; and means operatively connecting the stirrups with the sheave rotatably mounted upon the top of the car for the purpose of controlling the elevation of the said car by the spring actuated drum. 125

2. A foot operated elevator comprising a suitable car; a spring actuated drum rotatably mounted within the car; a sheave rotatably mounted within the car and above 130

- the spring actuated drum; stirrups slidably mounted within the car; a stationary suspension cable adapted to engage the periphery of the sheave and having its lower end wound around the spring actuated drum; sprockets rotatably mounted on either side of the sheave and adapted to rotate in opposite directions and to engage the said sheave when turning in one direction only; and suitable connections between the stirrups and the sprockets and adapted to rotate the said sprockets in opposite directions from each other so that one of the said sprockets will always be in engagement with the sheave when it is continuously rotating in one direction, for the purpose of controlling the elevation of the car by the spring actuated drum and suspension cable.
3. A foot operated elevator comprising a suitable car; a spring actuated drum rotatably mounted within the car; a shaft rotatably mounted on the top of the car and above the spring actuated drum; a sheave rigidly secured to the approximate center of the shaft and having clutch members on either side thereof; sprockets rotatably mounted upon the shaft and on either side of the sheave and having clutches adapted to engage the clutches on the sheave when turning in one direction only; a stationary suspension cable adapted to engage the periphery of the sheave and having its lower end wound around the spring actuated drum; stirrups slidably mounted within the car; suitable connections between the tops of the stirrups and adapted to engage the sprockets and rotate the same in opposite directions by pulling downward on one stirrup; means adapted to cause the clutches of either sprocket to engage the clutch on that side of the sheave when turning in the same direction therewith; and means for releasing both sprockets from the sheave.
4. A foot operated elevator comprising a suitable car; a sheave rotatably mounted on the top of the car; a stationary suspension cable adapted to engage the periphery of the sheave and to rotate the same; a spring actuated drum rotatably mounted within the frame and adapted to engage the lower end of the cable below the sheave and to wind the said cable around the said drum for the purpose of elevating the car; stirrups slidably mounted within the car; sprockets rotatably mounted on the top of the car and coaxial with the sheave and adapted to engage the sheave when rotating in the same direction therewith; suitable springs adapted to retain the sprockets against the sheave; suitable connections between the tops of the stirrups and adapted to rotate the sprockets in opposite directions; means for releasing both sprockets from the sheave; and means for controlling the descent of the car when both sprockets are released from the sheave.
5. A foot operated elevator comprising a suitable car; a sheave rotatably mounted upon the top of the car; a stationary suspension cable adapted to engage the periphery of the sheave and rotate the same; a spring actuated drum rotatably mounted within the car below the sheave and adapted to engage the lower end of the suspension cable and to wind the said cable around the said drum for the purpose of elevating the car; stirrups slidably mounted within the car; sprockets rotatably mounted on the car coaxial with the sheave and adapted to engage the sheave when rotating in the same direction therewith; suitable springs adapted to retain either sprocket in connection with the sheave when rotating therewith; suitable connections between the tops of the stirrups and having chain portions adapted to engage the sprockets and to rotate the said sprockets in opposite directions when one of the stirrups is pulled downward; levers adapted to disengage both sprockets from the sheave; and a suitable governor secured to the spring actuated drum and adapted to control the descent of the car when both sprockets are released from the sheave.

In witness whereof I hereunto set my signature in the presence of two subscribing witnesses.
